UNITED STATES PATENT OFFICE.

ROBERT MIEHLE, OF CHICAGO, ILLINOIS, ASSIGNOR OF ONE-HALF TO MIEHLE PRINTING PRESS & MANUFACTURING COMPANY, OF CHICAGO, ILLINOIS, A CORPORATION OF ILLINOIS.

PILING-TABLE FOR PRINTING-PRESSES.

1,089,842.

Specification of Letters Patent.

Patented Mar. 3, 1914.

Original application filed March 7, 1904, Serial No. 196,890. Divided and this application filed October 19, 1905, Serial No. 263,876. Renewed January 15, 1914. Serial No. 812,807.

To all whom it may concern:

Be it known that I, ROBERT MIEHLE, a citizen of the United States, residing at Chicago, in the county of Cook and State 5 of Illinois, have invented a new and useful Piling-Table for Printing-Presses, of which the following is a specification.

This invention relates to piling tables for receiving the sheets from a sheet delivery 10 of a printing press, or other machine, and it has more especial reference to devices of this nature for use in conjunction with that form of printing press in which the ink fountain and apparatus is arranged at one 15 extremity of the stroke of the bed, and which, as heretofore constructed, is usually situated directly under the piling table, or other sheet-receiving surface. This relative location of the piling table and ink fountain 20 is found very objectionable, in that the ink fountain and apparatus is not readily accessible during the operation of the press, and even at other times is awkward of management, and requires the table to be 25 moved; and furthermore, what is probably a more serious objection, is, that it very materially curtails the range of vertical movement of the piling table, rendering it incapable of being started at a high elevation 30 and lowered close to the floor while receiving sheets.

One of the important objects of this invention, therefore, is to provide for a wide range of vertical movement of the piling table, or sheet receiving surface, which is accomplished by arranging the actuating 35 shaft of the adjusting mechanism of the receiving surface in such a position with respect to the surface that it will not project 40 over the edge of the surface into the path of the upward or downward movements thereof, and so that the shaft will be located to one side of the surface and also of the 45 pile of sheets on the receiving surface; a further object being to afford this wide range of movement of the piling table while rendering it possible to connect it with a press for automatic operation thereby.

With a view to the attainment of these 50 ends, and the accomplishment of certain other objects which will hereinafter appear, the invention consists in the features of novelty, in the construction, combination, and ar-

rangement of parts, which will now be described with reference to the accompanying 55 drawings, and more particularly pointed out in the claims.

In the said drawings,—Figure 1 is a side elevation of my improved printing press. Fig. 2 is an enlarged detail view hereinafter 60 described. Fig. 3 is a side elevation of the press looking from the opposite side to that presented in Fig. 1. And Fig. 4 is a plan view thereof.

The printing press proper is of a well 65 known type of flat bed press comprising, among the usual features of mechanism, an ink fountain or apparatus A, arranged at one end of the stroke of the bed, and supported in the usual manner upon the main frame 70 1, at the opposite end of which is journaled the usual impression cylinder B. This ink fountain or apparatus in presses of this character has heretofore been mounted under the sheet piling table, downwardly toward which the sheet-conveying tapes 2 conduct the sheet to a position over the sheet delivery, which may be of the well-known fly-finger type or reciprocating carrier.

The piling table constructed in accordance with the present invention is adapted 80 for use with conveyer tapes 2 which are supported at an elevated position by an upwardly extending frame 3, high above the ink fountain A, so as to deliver the sheets 85 to the supporting surface from overhead, and the piling table C is set off from the ink fountain A at a considerable distance therefrom so as to form a passage-way D between the table or other sheet receiving 90 surface and such fountain, whereby the workman or attendant may pass freely between the table and the fountain, and free access to the fountain and other parts of the inking apparatus may be had during 95 the running of the press, and at all other times.

The sheet piling table C, or other sheet receiving surface, is supported at a considerable elevation in a suitable frame 4, which 100 also serves as a means for supporting the ways or tracks 5, 6, for the sheet carrier carriages 7, 8, at one end, while the opposite ends of these ways 5, 6, are supported by extensions 9, 10, of the frame 3. The sheet 105 delivery mechanism itself may be of the

usual or any suitable form, such as the double interchangeable form of reciprocating sheet carrier and fly finger delivery shown in my United States Patent No. 610,491, granted Sept. 6, 1898, to which reference may be had for an understanding of the construction and operation of any details of the delivery not herein illustrated, and also shown in my U. S. Patent #909,199, issued January 12th, 1909. The carriages 7, 8, constituting a portion of the reciprocating sheet carrier, are given their necessary reciprocating travel on the ways 5, 6, but suitable operative connections extending across the passage-way D to the operating mechanism of the press proper, and these connections, as also the connections for operating the fly fingers to be presently described, instead of being carried across the passage-way D near the floor line, which would bring them in the way of the feet of the attendant, are preferably carried across at an elevation high above the ink fountain or mechanism. With this arrangement it will be apparent that the actuating shaft of the table will be located to one side of the sheet receiving surface so that no portion of such shaft will project over the edge of the table or surface into the path of the adjustment of the table upwardly or downwardly. The reciprocating sheet delivery mechanism is operated by two links 19, 20, which are respectively connected with vibratory arms or levers 21, 22, secured to a rocker shaft 23, which latter is journaled in the frame extensions 9, 10, and to one side of the piling table or surface, and this shaft is rocked by an arm 24, as shown and described in my aforesaid patents. The shaft 23 is rocked from a crank 28 on the shaft 29 through the medium of the rod 27, lever 26 and rod 25, and the fly operating cam 30 is also actuated by the shaft 29, and these parts are adapted to be rendered inactive in the manner set forth in the last recited patent. The rocker shaft 16 is actuated by the shaft 33 to which latter it is connected by the usual pinion or toothed segment 34 engaging with a rack-bar 35 arranged above it on the end of a connecting rod 36 extending to another pinion or toothed segment 37 secured to the rocker shaft 16 and engaging a rack-bar 38 secured to or formed on the outer end of rod 36, the two rack-bars 35, 38, being arranged to slide in suitable keepers 39, 40, pivoted around the centers of shafts 16, 33, respectively, similar to the keeper 23 shown and described in my aforesaid patent. Thus it will be seen that when the shaft 33 is oscillated, similar oscillation will be imparted to the rocker shaft 16, and consequently the fly fingers 15 will be moved back and forth, resting below the tapes 2, until the sheet arrives at the limit of its travel on said tapes, and then rising

between the tapes in the usual way for flying the sheet and delivering it upon the piling table.

The pinion or segment 32 on the shaft 33, which latter in my former patent aforesaid served as a means of supporting and oscillating the fly fingers, derives oscillation or back and forth rotation in the usual way from cam 30, that is to say, by a lever 41 pivoted to frame 1 and carrying an anti-friction roller 42 adapted to be held in contact with the periphery of cam 30 by a spring 43 on a connecting rod 44 pivoted at one end to lever 41 and having its other end provided with the usual rack-bar 45 sliding in the usual keeper 46 and engaging pinion 32. When the reciprocating carrier is to be used, the lever 41 is held out of action by any suitable stop 47.

48 is the usual spring-actuated rod connected by a crank 49 to fly finger shaft 16 for assisting in throwing the fly toward the table, as well understood, the rod being supported in this instance on the side of frame 4 in an upright position in suitable guides 50, 51.

By thus locating the piling table C at a distance from the inking apparatus, I not only provide a passage-way between it and the inking apparatus, but I very materially increase the receiving capacity of the table, and am enabled to make the table vertically adjustable throughout a wide range of movement above the floor, which adjustment will not be interfered with by the projection of any portion of the actuating shaft projecting into the path of the adjustment of the table or receiving surface. To this end, therefore, the table is supported at both sides by vertical screws 52, 53, journaled in the frame 4 and having threaded connection with the table, so that when the screws are rotated the table will descend or ascend according to the direction of rotation. The upper ends of these screws 52, 53, are connected together by a counter-shaft 54 journaled across the inner side of the frame 4, and to one side of the table and which countershaft has at its ends two sprocket wheels 55, 56, which are connected respectively by chains 57, 58, with sprocket wheels 59, 60, on stud shafts 61, 62, journaled in suitable brackets 63, 64, on top of frame 4, and having bevel gear connection 65, 66, respectively, with the upper ends of screws 52, 53, so that the screws will be driven in unison when the shaft 54 is rotated. The shaft 54 is thus rotated automatically by any suitable connection with the sheet delivery mechanism. This connection for the reciprocating form of delivery comprises a long pawl 67 pivoted to rocker arm 24 and arranged to engage a ratchet wheel 68 secured to shaft 54, each time the rocker arm makes a back-

ward movement, thus rotating the shaft 54 a sufficient distance to lower the table C approximately a distance equal to the thickness of a single sheet of paper, or equal to 5 the thickness of a plurality of sheets if a plurality be delivered upon the table at one time, the extent of the effective action of the pawl 67 being regulated by a deflecting cam 69 adjustably secured at 70 to the side of 10 frame 4 and serving to hold the point of the pawl out of engagement with the ratchet wheel throughout a greater or less extent of its stroke. The means for rotating the ratchet by the action of the fly fingers is 15 shown in Fig. 2, and consists of a pawl 71 pivoted detachably to a short crank arm 72 secured on the end of fly finger rocker shaft 16, and capable of being thrown back out of the way or removed when the reciprocating 20 delivery is to be used.

The table may be raised or lowered rapidly by hand when desired, through the agency of a crank 73 secured to shaft 54. By thus connecting the vertical screws of 25 the table mechanism to a countershaft located at any point out of the range of both the table itself and the fly, it will be seen that I am enabled to impart movement to the table automatically without interfering 30 in any way with the movement of the delivery or curtailing the range of movement of the table, or interfering with the introduction of a truck under the table for allowing the latter to be loaded directly onto it in 35 case it should be desired to do so.

Claims for the overhead sheet delivery mechanism shown and described, but not claimed herein, constitute the subject matter of the claims of my application No. 196,890, 40 filed March 7, 1904, now Patent No. 909,199, issued January 12, 1909, of which this application is a division.

Having thus described my invention, what I claim as new therein, and desire to secure 45 by Letters Patent, is:

1. A piling table of the class described comprising a table proper arranged to move from an overhead position to a position near the floor, a horizontal rocker-shaft arranged 50 out of the path of movement of the table and operatively connected therewith for lowering the same, a counter-shaft adjacent the said rocker-shaft and lengthwise thereof, and means operatively connecting said 55 counter-shaft with the rocker-shaft for operating the former.

2. A piling table of the class described comprising a table proper arranged to move from an overhead position to a position near 60 the floor, a horizontal rocker-shaft arranged out of the path of movement of the table and operatively connected therewith for lowering the same, a counter-shaft adjacent the said rocker-shaft and lengthwise there-

of, means operatively connecting the said 65 counter-shaft with the rocker-shaft for operating the former, and additional means for lowering the said table at will.

3. A piling table of the class described, comprising a sheet receiving surface situated in an overhead position, mechanism for lowering said surface embodying a horizontal shaft arranged in an overhead position and to one side and out of the path of movement of the said surface, said mechanism 70 also embodying connecting means between the said surface and the shaft, and mechanism for imparting motion to the shaft.

4. A piling table of the class described 80 comprising a sheet receiving surface situated in an overhead position, mechanism for lowering said surface embodying a shaft arranged to one side and out of the path of movement of the said surface, said mechanism 85 also embodying connecting means between the said surface and the shaft, mechanism for imparting motion to the shaft, and a hand crank connected with the shaft for raising and lowering said surface at will. 90

5. In combination, a vertically movable piling table, mechanism for moving said piling table in a vertical direction and embodying upright screws operatively connected with the table, sprocket wheels operatively connected with the screws for imparting motion thereto, a shaft arranged to one side of the plane of movement of the said table, sprocket wheels connected with the shaft for movement therewith, sprocket 100 chains engaging the respective sprocket wheels connected with the screws and shaft, and means for operating the shaft.

6. In combination, a vertically movable piling table, mechanism for moving the piling table in a vertical direction and embodying upright screw shafts arranged on opposite sides of and connected with the piling table, stub shafts arranged adjacent the upper extremities of the screw shafts on 105 axes transverse to the axes of the vertical screws, gear connections between the stub shafts and the respective screws, and sprocket wheels operatively connected with said stub shafts, a counter-shaft arranged 110 to one side of the plane of movement of the piling table, sprocket wheels mounted upon said countershaft for rotation therewith, sprocket chains engaging the sprocket wheels on the last recited shaft and the respective wheels on the stub shafts, and means 115 for rotating the countershaft.

7. In combination, a vertically movable piling table, mechanism for moving the piling table in a vertical direction and embodying upright screw-shafts arranged on opposite sides of and connected with the piling table, stub-shafts arranged adjacent the 125

upper extremities of the screw-shafts on axes transverse to the axes of the vertical screws, gear connections between the stub-shafts and the respective screws, sprocket 5 wheels operatively connected with the said stub-shafts, a counter-shaft arranged to one side of the plane of movement of the piling table, sprocket wheels mounted upon the counter-shaft for rotation therewith, 10 sprocket chains engaging the sprocket wheels on the last recited shaft and the re-

spective wheels on the stub-shafts, means for rotating the counter-shaft, and additional means connected with the counter-shaft for raising and lowering the table at will.

15

In witness whereof, I have hereunto set my hand this 16th day of October 1905, in the presence of the subscribing witnesses.

ROBERT MIEHLE.
